UNITED STATES PATENT OFFICE.

HENRY H. SANFORD, OF MANSFIELD, OHIO, ASSIGNOR TO NEW METHOD STOVE COMPANY, OF MANSFIELD, OHIO, A PARTNERSHIP COMPOSED OF HENRY H. SANFORD, BERNHARD R. AHRENDT, EDWIN D. BAXTER, AND BERRY A. BAXTER.

STOVE.

1,227,676.

Specification of Letters Patent. Patented May 29, 1917.

Application filed March 29, 1916. Serial No. 87,640.

To all whom it may concern:

Be it known that I, HENRY H. SANFORD, a citizen of the United States of America, residing at Mansfield, in the county of Rich-
5 land and State of Ohio, have invented cer-
tain new and useful Improvements in
Stoves, of which the following is a specifi-
cation.

The invention relates to an improved
10 stove constructed with a view to providing
means in the same stove body, for the burn-
ing of a gaseous or solid fuel as may be
desired.

In natural gas regions, there is constant
15 liability to low pressure periods, during
which the gas is not properly available as a
fuel, and furthermore, in some of such re-
gions the natural pressure is gradually be-
coming less. It is therefore of importance
20 that, particularly for such regions, means
should be devised which will adapt a stove
for the use of gaseous fuel, when such is
properly available, and yet permit the stove
25 to be readily used for solid fuel, upon fail-
ure of the gas supply or the exhaustion of
the gas.

The present stove is designed particularly
with a view to permitting the use of gaseous
fuel or solid fuel at the will of the user, the
30 conversion of the stove from one type to
the other involving merely the removal of
the burners for the gaseous fuel.

In the stove structure to which the present
invention is directed, there are certain de-
35 tails which are of importance in a com-
bined type of stove, particularly the ar-
rangement of the smoke flues; the means for
conducting the products of combustion all
around the oven; means for securely closing
40 all of those openings in the stove arranged
to permit the insertion or attachment of gas
burners when it is desired to convert the
stove for the burning of solid fuel; and
means for directing the fumes of the cook-
45 ing to pass directly into the smoke flue when
gaseous fuel is being used, and check the
fire when solid fuel is used.

The invention in the preferred form of
details will be described in the following
50 specification, reference being had to the ac-
companying drawings, in which:—

Figure 1 is a view in elevation of the im-
proved stove;

Fig. 2 is a side elevation of the same;

Fig. 3 is a broken plan of the same; 55

Fig. 4 is a broken sectional view illustrat-
ing particularly the closure for the opening
above the oven;

Fig. 5 is a longitudinal section through
the body of the stove; 60

Fig. 6 is a sectional view on line 6—6
of Fig. 5.

The stove of the present improvement is
here shown as what may be termed the con-
ventional form, although it is to be under- 65
stood that the details of structure are in no
wise limited to this particular form. The
stove is preferably constructed to provide
the usual body 1, in the form of a rectangu-
lar casing of appropriate size having the 70
overhanging top 2, from which at the rear
rises the usual back 3, the stove as an en-
tirety being supported upon legs 4, or the
like, the various parts of the stove just de-
scribed being constructed as preferably in 75
the form illustrated in the drawings, and
of course of wrought metal. The interior
of the stove body is divided by a trans-
versely arranged partition 5 which rises
from the bottom of the stove, and extends 80

for the full width thereof, terminating short
of the top, however, as will be seen in Fig.
5. The partition divides the stove into
spaces of unequal length, the space of
shorter length being adapted to receive in 85

the relatively upper portion thereof, any ap-
propriate form of solid fuel receiver 6, such
as a fire-pot, grate, or the like, the said fuel
receiver having what may be termed its
inner wall terminating on a line with the 90
top of the partition, so that the fuel space
is in open communication with the space be-
yond the partition 5. Arranged within the
remaining space of the body is an oven 7,
of rectangular formation having its respec- 95
tive front and rear wall coincident with the
similar walls of the body and its side walls
8 and top and bottom walls 9 and 10 spaced
from the similar walls of the body to pro-
vide flues 5', 11, 11' and 11² entirely sur- 100
rounding the oven. The upper wall 9 of
the oven is extended laterally to engage the
upper end of the partition 5, as at 12, and
a baffle plate 13 is secured to the side wall of
the oven next the flue space 5', said baffle 105
plate extending from the rear limits of the
oven to a point somewhat spaced from the
forward limits thereof, and of a height to

close the flue 11² throughout the longitudinal extent of the baffle plate. The baffle plate thus interposes an opposition in the flue 11² to the direct flow of the heated products, compelling said products to pass around the baffle plate before reaching the vertical portion of the flue 5' next the fuel receiving space.

The back 3 of the stove, throughout that vertical half of the stove proper which includes the fuel receiving space, is extended for the full normal height of such back, and provided at the upper end with what may be termed a canopy 14 and below the same with a shelf 15, the usual side walls 16 being provided. The remaining half of the back extends for a short distance above the stove body as at 17 and the remaining distance is taken up by a gas oven 18, the detail structure of which is unimportant with respect to the present invention, it being understood that it is provided with the usual broiling and baking receptacles 19 and 20, fuel pipe 21, and such accessories as are necessary to complete the structure.

The disposition of the oven with respect to the remaining portion of the back is an important detail of the present invention, as it will be obvious that the oven supported largely from brackets 22 rising from the stove body is arranged so that it projects rearwardly beyond the back proper, so that there is thus provided at the juncture of the back and projecting portion of the oven, angularly related sections in which the smoke pipe 23 is snugly received and secured. The oven top constitutes in effect an extension of the canopy so that by this arrangement there is provided a means for rigidly securing the smoke pipe in place, while avoiding any obstruction to the top portion of the stove. The smoke pipe 23 terminates at its lower end in what may be termed a flue box 24, of increased sectional dimension as compared with the similar dimension of the smoke pipe, and so located as to include or register with the flues 5' and 11 about the oven, both above and below the extension 12 of the top wall 9 of the oven. The flue 5' below the cross partition 12 communicates directly with the flue box through an opening 25 in the rear wall of the stove body, that portion of the flue above the top wall of the oven also communicating with the flue box through an opening 26. This opening 26 is comparatively elongated, and controlled through a damper plate 27, fixed upon a rod 28, pivotally mounted on the inner side of the rear wall of the body as at 29, and projecting beyond the side wall of the body in the form of a handle 30 for convenient operation. The forward wall of the stove is provided with the usual door closed openings 31 and 32 providing access respectively to the oven and to the space in the fuel

chamber below the receiver 6, for draft purposes, removal of the ashes and the like.

The stove so far described is particularly designed for use with solid fuel, although its construction is such as to render it particularly designed for such modifications as will permit it to be readily converted into a gaseous fuel stove when desired. To this end it is to be understood that means must be provided for the introduction of the usual gas burners when gaseous fuel is to be used, and to provide means for closing the stove body upon the withdrawal of the said gas burners in order that the stove might be adapted for solid fuel.

In providing for the use of gaseous fuel the forward wall of the stove above the upper limits of the oven 7 is formed with an opening 33, which registers with the flue 11 and is of somewhat less length than the length of the stove on one side of the partition 5. The opening 33 is provided with a door or closure 34, hinged at 35 to the front wall of the stove and adapted to pivot upwardly when desired to completely close the opening 33. In its lowered or opened position, the closure 34 rests upon the top 9 of the oven, as clearly shown in Fig. 4, and it is adapted to be maintained in its closed position when desired by a turn button 36 pivotally mounted on the wall of the stove adjacent the closure and operable from the outer side of the stove. The forward wall of the stove on the opposite side of the partition 5 in longitudinal alinement with the opening 33 is formed with an opening 37, for the reception of a burner, this opening when not in use to receive the gaseous burner, being designed to be closed by a door or closure 38 pivotally mounted on the stove wall and operable in an obvious manner as will be plain from Fig. 1 of the drawings. The above top 2 is provided with the usual openings 39 adapted to be closed by the lids 40 and these openings are preferably arranged so that upon the introduction of the gas fuel burners 41 the said burners will register with the openings so that in the use of the stove for burning gas the removal of the lids provides the ordinary gas burners permitting direct application of the heat to the utensil. The burners 41 are mounted in any manner to properly support the burners interiorly of the stove, it being understood that the connected parts include the control valves, air admission ports, and the like, as is common in burners of this type.

The back 3 immediately beneath the canopy 14 is formed with an opening 43 which communicates directly with the smoke flue 23, any suitable form of damper or cut-off 44 controlling this opening. The opening is arranged to permit the fumes to escape when gaseous fuel is being used and to operate as a check damper in the use of solid fuel.

In the use of the stove for gaseous fuel, the closures 34 and 38 are turned to expose the openings and the gas burners in completed form are inserted in place. In this 5 arrangement the damper 27 is turned to its closed position and the stove used as an ordinary gas stove. In the use of solid fuel the closures 34 and 38 are operated to close the opening after the removal of the burners 10 and connected parts, the fuel is introduced into the grate or receiver 6, and the damper 27 turned down to permit the products of combustion to flow directly into the smoke flue, until a proper burning of the fuel is 15 attained, whereupon the damper is closed and the products of combustion compelled to reach the smoke flue through a complete circulation about the oven through the flues 11, 11', 11² and 5'. The baffle plate 13 forces 20 a lateral movement of the products of combustion in a direction opposite the smoke flue to insure a more effective heating result from such products. During the use of the stove as a gas stove, the damper 44 may be 25 opened to permit the fumes from the cooking and the like to escape directly into the smoke flue, and the said damper is also effective in providing a means for checking the fire by interfering with the direct draft in 30 the use of the stove as a solid fuel stove.

The essential and important features of the present invention reside in the relative arrangement of the gas oven and back whereby to provide an offset in the angle 35 of which the escape flue may be located to most advantageously position the same for its functions; the arrangement whereby the stove may be readily and quickly convertible for the reception of gas burners or completely closed for the use of solid fuel; the 40 damper control whereby in the use of gaseous fuel a direct outlet is provided and in the use of a solid fuel flues arranged about the oven through which the products of combustion must find their way to reach the escape flue; and the provision of a damper controlled outlet, which in the use of the 45 article as a gas stove, provides for the escape of fumes from cooking and in the use 50 of the stove as a solid fuel stove operates as a check damper.

Another essential feature consists in providing an extra flue or chamber between the fire pot and oven.

55 What is claimed is:

1. A combined gas and solid fuel stove including a stove body having a vertical partition terminating below the top of the body to provide a communication between the 60 spaces on opposite sides of the partition, an oven arranged in one space and having its top wall coincident with the height of the

partition and engaging therewith, the top, sides and bottom of the oven being spaced from the similar portions of the body and 65 partition to provide a flue about the oven, the connection of the top wall of the oven and the partition breaking the continuity of the flue, an escape flue arranged beyond the body and disposed above and below the top 70 wall of the oven, the body wall being formed with independent openings to establish communication between said flue above the oven, and the escape flue immediately adjacent and on opposite sides of the top wall of the 75 oven at its juncture with the partition, a canopy rising from the stove body and having a cut out portion, and an oven arranged in such cut out portion and projecting rearwardly of the canopy to form therewith 80 angularly related portions and receive the escape flue.

2. A combined gas and solid fuel stove including a stove body having an upright back, an oven arranged in a cut out portion of the 85 back and projecting rearwardly of the same to cause one side wall of the oven to form with the back angularly related meeting surfaces, and an escape flue in communication with the stove body and secured in the angle 90 of such meeting surfaces.

3. A combined gas and solid fuel stove, including a stove body having a vertical partition terminating below the top of the body to provide open communication between the 95 spaces on opposite sides of the partition, a grate arranged in one of said spaces, an oven arranged in the other of said spaces and having its top wall coincident with the height of and connected to the partition, the top, 100 sides, and bottom of the oven being spaced from the stove body to provide a flue about the oven, the connection of the top wall of the oven and the partition breaking the continuity of the flue, an escape flue communicating with the flue about the oven immediately adjacent and both above and below the junction of the top wall of the oven and the partition, a damper controlling the communication above the oven wall, the stove body 110 in horizontal alinement with the space above the oven being formed on each side of the partition with openings having closures, and removable gas burners adapted to be inserted through said openings to rest respectively above the grate and above the oven, whereby the heat products from the fuel in the grate or from the gas burners may be directed about the oven or to the flue independently of the oven.

120 In testimony whereof I affix my signature.

HENRY H. SANFORD.
